(57) **CLAIM**

The ornamental design for an electric bicycle frame, as shown and described.

DESCRIPTION

1. Electric bicycle frame

1.1 is a left side elevation view of an electric bicycle frame embodying our new design;

1.2 is a right side elevation view thereof;

1.3 is a front elevation view thereof;

1.4 is a rear elevation view thereof;

1.5 is a top plan view thereof;

1.6 is a bottom plan view thereof; and

1.7 is a rear and right side perspective view thereof.

1 Claim, 7 Drawing Sheets
